No. 655,073.

Patented July 31, 1900.

L. GODBOUT.
LEATHER CRIMPER.

(Application filed Mar. 21, 1900.)

(No Model.)

UNITED STATES PATENT OFFICE.

LOUIS GODBOUT, OF WYANDOTTE, MICHIGAN.

LEATHER-CRIMPER.

SPECIFICATION forming part of Letters Patent No. 655,073, dated July 31, 1900.

Application filed March 21, 1900. Serial No. 9,593. (No model.)

To all whom it may concern:

Be it known that I, LOUIS GODBOUT, a citizen of the United States, residing at Wyandotte, in the county of Wayne and State of Michigan, have invented a new and useful 5 Leather-Crimper, of which the following is a specification.

This invention relates to a leather-crimper for crimping a shoe-upper; and the object of 10 the same is to provide simple and effective means for forming a shoe-upper from a single piece of leather and giving it the proper form and shape by pursuing the ordinary methods of crimping on the improved device, 15 the latter having adjustable and separable features to render it convenient in effectively carrying out the several crimping operations.

The invention consists in the construction 20 and arrangement of the several parts, which will be more fully hereinafter described and claimed.

In the drawings, Figure 1 is a perspective view of a crimping device embodying the 25 features of the invention. Fig. 2 is a sectional side elevation of the improved crimping device. Fig. 3 is a perspective view of the lower portion of the crimping-block shown inverted. Fig. 4 is a perspective view 30 of a portion of the intermediate support to which the crimping-block is removably attached.

Similar numerals of reference are employed 35 to indicate corresponding parts in the several views.

The numeral 1 designates a crimping-block 40 comprising a front section 2, to which is adjustably applied a rear section 3. The lower portion of the section 2 has a foot extension 4, which is continuous with a vertical member 5, conforming in contour, approximately, 45 to the ankle and adjacent limb portion of a shoe-upper. The rear section 3 is also shaped to correspond to the natural form of the heel and rear portions of the ankle and adjacent limb and has upper and lower angular recesses 50 6 and 7 for a purpose which will be presently set forth. The rear section 3 is freely adjustable toward and away from the section 2, and the contiguous faces of the two sections, as at 8, are straight, so that when both faces abut or coincide to reduce the block to its minimum size the two sections will be virtually continu-

ous and without lateral projections or shoulders. In the upper and lower portions of the face 8 of the section 3 metallic screw blocks or 55 nuts 9 and 10 are mounted and countersunk or embedded in the said section, so as to have one face of each flush with the adjacent face 8. The nuts 9 and 10 are of angular form or so shaped that when disposed in recesses of similar form they will be prevented from turning, and thus serve efficiently to coact and give bearing to adjusting screw-rods 11 projecting into the recesses 6 and 7 in the upper and lower portions of the section 3 and through 65 the said section partially into the section 2, the front ends of said adjusting-rods being grooved, as at 12, and held by slotted swivel-plates 13, relatively located in the section 2 and formed of metal to resist wear, the said 70 plates being let into slots 14 and of less length than the latter, and to fill the slots suitable strips or pieces 15 of wood or material similar to that of which the sections of the crimping-block are formed are used. Secured to 75 the upper and lower ends of the section 3 are gage-plates 16, provided with suitable scales, as shown by Fig. 3, and freely movable over the adjacent end portions of the section 2, so that the adjustment at opposite portions of the 80 block may be regularly made and to correspond to different sizes of shoes to be crimped. It will be observed that when the section 3 is adjusted to or from the section 2 by manipulating the adjusting-rods 11 the gage-plates 85 16 will be correspondingly moved, and, moreover, it is possible to make the sections of the block stand in regular relation to each other or have them spaced at irregular distances at 90 opposite extremities and in accordance with the measurements to be followed in crimping the leather for a particular upper.

The entire block is sustained in working position by the section 2, which has a lower longitudinally-disposed rib 17, with upwardly 95 and inwardly beveled side edges 18 to removably enter a longitudinally-disposed corresponding slot 19 in the upper horizontal member 20 of an intermediate support 21, the latter also comprising a vertical member 22, having a horizontal cylindrical shank 23 projecting forward therefrom and provided with a spirally-threaded extremity 24. The shank 23 is rotatably mounted in the upper portion

of a stand 25, which is supplied with a vertical socket 26, adapted to receive a vertical post or upright on a suitable base-rest and permit the said stand to be swung thereon in a horizontal plane, and thereby simultaneously adjust the block above in the same direction. The stand 25 has a foot 27 projecting from one side, which serves as a brace to support the block above with stability during the crimping operation, and on the screw or spirally threaded extremity 24 of the shank 23 a swing-clamp 28 is adjustably fitted and provided with a radial arm 29, adapted to be thrown into contact with opposite portions of the stand to serve as a lock for the clamp and to maintain the degree of adjustment of the shank or so that the intermediate support 21 may be disposed obliquely to the stand and so held while working or crimping the leather on the block above and for the convenience of the operator.

In operation the sections 2 and 3 are adjusted or arranged by the movement of the section 3 to accommodate the size of the upper to which the leather is to be worked down by crimping, and the leather is then placed on the complete crimping-block in a wet condition and subjected to the usual crimping operations of rubbing and other surface treatment to bring it to the shape of the block, and during such operation the block may be turned horizontally at will or moved obliquely to a vertical plane and fixed by the means set forth and also simultaneously swung in a horizontal plane by the rotation of the stand 25 and obliquely arranged through the shank 23 to accommodate the position desired and fixed to maintain its angular position. The usual methods of fastening the upper-leather are employed, and after the crimping operation has been completed the crimping-block as an entirety can be removed from the intermediate support 21 by grasping the section 2 and drawing it forwardly, so as to relieve the rib 17 from the frictional binding action of the walls of the slot 19 in the horizontal member of the support 21. The block may afterward be applied and held on the support 21 by reinserting the rib 17 in the slot 19, and to permit

a firm grip on the block 2 to be obtained the lower rear portion of the section 2 thereof is provided with opposite recesses 30, as clearly shown in Figs. 1 and 2.

It will be understood that the sections 2 and 3, as well as the remaining features of construction explained, will be formed of suitable wood by preference and of that character usually employed in constructing boot-trees, lasts, and the like. It will also be understood that one crimping device may be employed for making various sizes of shoe-uppers or of treating said uppers thereon in the manner set forth; but it is intended to vary the form, portions, and size of the several parts as well as resort to changes in minor details without departing from the principle of the invention.

Having thus described the invention, what is claimed as new is—

1. A crimping device comprising a crimping-block transversely divided at the rear to form two sections one of which is adjustable on the other, a laterally-rotatable intermediate support to which the front section of the crimping-block is removably attached, and a rotatable stand carrying the said support.
2. A crimping device comprising a crimping-block transversely divided at the rear to form two sections one of which is adjustable on the other, and an adjustable support to which the front section of the crimping-block is removably attached.
3. A crimping device comprising a crimping-block transversely divided at the rear to form two sections, one of which is adjustable on the other, gage-plates attached to the upper and lower portions of the said adjustable section and freely movable over portions of the other section, and an adjustable support to which the front section of the block is removably attached.

In testimony that I claim the foregoing as my own I have hereto affixed my signature in the presence of two witnesses.

LOUIS GODBOUT.
